UNITED STATES PATENT OFFICE.

JOSEPH ZWEIG, OF BROOKLYN, NEW YORK, ASSIGNOR TO METROPOLITAN LAMP CO., INC., OF NEW YORK, N. Y., A CORPORATION OF NEW YORK.

DESIGN FOR A TELEPHONE CABINET.

Application filed May 24, 1928. Serial No. 26,841. Term of patent 3½ years.

To all whom it may concern:

Be it known that I, JOSEPH ZWEIG, a citizen of the United States, residing in the borough of Brooklyn, county of Kings, city and State of New York, have invented a new, original, and ornamental Design for Telephone Cabinets, of which the following is a specification, reference being had to the accompanying drawing, forming a part thereof.

The drawing shows a perspective view of the article, showing my new design.

I claim:—

The ornamental design for a telephone cabinet substantially as shown.

JOSEPH ZWEIG.
